(57) **CLAIM**

The ornamental design for a rocking cradle, as shown and described.

DESCRIPTION

FIG. 1 is a perspective view of a rocking cradle showing our new design;

FIG. 2 is an additional perspective view thereof;

FIG. 3 is a right side view thereof;

FIG. 4 is a bottom view thereof;

FIG. 5 is a left side view thereof;

FIG. 6 is a top view thereof;

FIG. 7 is a front view thereof; and,

FIG. 8 is a rear view thereof.

The portions shown in broken lines depict environmental subject matter only and do not form any part of the design.
